WINDOW CONSTRUCTION

David E. Ross, La Fayette, Ind., assignor to Rostone Incorporated, La Fayette, Ind., a corporation of Indiana

Application July 18, 1932. Serial No. 623,266

11 Claims. (Cl. 189—75)

This invention is a novel window construction, including novel glazed metallic sash, novel metal framing or housing for such sash, and novel weather stripping.

The objects of the invention are to provide a window frame and sash having great rigidity of structure; weatherproof and soundproof in construction to eliminate counter weights or counter springs; and at the same time secure a 100% opening of the window if so desired.

I will explain the invention with reference to the accompanying drawings and summarize in the claims the essential features of construction and novel construction and combination of parts 15 for which protection is desired.

In said drawings:

Fig. 1 is a front view partly broken away of a metal window frame and glazed sash embodying the invention.

Fig. 2 is a vertical section on the line 2—2, Fig. 1.

Fig. 3 is a transverse section on the line 3—3, Fig. 2.

Fig. 4 is a detail section on the line 4—4, Fig. 1.

Fig. 5 is a front view of the lower part of a modified window frame and sash.

Fig. 6 is a vertical section on the line 6—6, Fig. 5.

Fig. 7 is a transverse section on the line 7—7, Fig. 6.

Fig. 8 is a detail section on the line 8—8, Fig. 5.

Fig. 9 is a detail plan view of one of the sash operating devices.

Fig. 10 is a view of the glazed metal sash partly in section.

Fig. 11 is a top view of Fig. 10.

Fig. 12 is a transverse sectional view through Fig. 10.

Fig. 13 is an enlarged detail view of the weather stripping devices shown in Fig. 2.

Fig. 14 is an enlarged detail view of the weather stripping devices shown in Fig. 4.

To facilitate an understanding of the complete invention, I will first describe the glazed window sash (see Figs. 10, 11 and 12). The construction of the novel sash is based upon the well known rigidity of heavy glass. Preferably, I use a sheet of plate glass 1 approximately $\frac{1}{4}$ " thick and of a size approximating the desired glazed window opening. This plate is enclosed in a frame consisting of opposite side bars 2 and 3 connected by rods 4, 4'. Bar 2 has a channel in one side into which one edge of the

plate 1 is inserted; and at the bottom of the channel there is a resilient member 2r, preferably of plastic or non-oxidizing rubber; and on the outer side of bar 2 is a rack 2n adapted to be operated by a spur gear, as hereinafter described.

The bar 3 at the other end of the plate is grooved to receive the edge of the plate, and a resilient member 3r similar to 2r is inserted in the groove. Bar 3 is of slightly less cross section dimension than bar 2, so that it is to be free in the standard ways in which the sash works. The rods 4, 4' are bolts connecting the bars 2 and 3 for clamping the glass plate 1 to and between said bars 2 and 3.

The glass plate 1 will not warp or sag; and is held tightly clamped between the bars 2 and 3. The parts 3, 4 and 4' stick out from bar 2 as a cantilever, and the resilient liners 2r, 3r allow for unequal coefficients of expansion between the metal frame and the glass. It is obvious that if the gear teeth or rack 2n on bar 2 were omitted and hinges substituted; then this assembly could be operated as a casement window. The part 2, being very long in comparison to its thickness and breadth, cannot possibly get diagonal and "cock" in the ways in which it has an easy sliding fit for ease of manipulation; while the part 3 preferably does not touch the sides of the ways. The structure can be made weather proof in the frame as hereinafter described. The said sash forms the subject matter of a divisional application.

These metal sashes are preferably mounted in a metal frame as hereinafter described and the glazed metal sash being very narrow a number of such sashes can be readily assembled within a narrow frame and within a small space. In the drawings I have shown metal frames in which a plurality of such sashes are mounted, each being independently operable.

The frame is preferably made of sheet metal as shown at 50 (see Fig. 2), this frame having an exterior upturned flange 50a and interior down-turned flange 50b. This frame could be made of standard channels allowing both flanges to turn out or both flanges to turn in. I obtain great over all depth of flange by turning one flange out and one flange in, and also obtain great depth of structure and, therefore, great rigidity by the construction shown. The standard rollings are cut at a mitre so they fit the corners forming a perfect rectangle and being welded at the corners form an integral frame of great rigidity.

The interior of the frame would be about twice the vertical length of the glazed sash so that when the sashes are lowered as in Figs. 1 and 2 they will be entirely exposed but they can be raised into the upper part of the frame so as to open the window. On the sides of the frame are attached ways 5, 7 and 8 and the three sashes W', W^c, W^o, and these ways may be attached to plates 11, 11' below and 12, 12' above (see Fig. 1) so that any sash can be removed or replaced. In general, the ways would probably be best welded to the side strips 11, 11' while the upper guides would be welded to 12, 12'. However, these guides for the glass may be fastened in any conventional manner.

In the construction shown in Figs. 1 to 3, W' is an inside glass sash (see Fig. 2); W^c a glass sash which may be an art window sash either of colored glass, transparent pictures, or other forms of art to be applied; while W^o is an outside or storm window sash. This assembly is desired where the space within the wall permits of all the glass retiring into the space above. The close nesting of this glass permits of a fly screen being placed in ways S just outside of W^o which screen can be raised up into the space above when it is not needed. At the inner side there are ways C for a curtain. This curtain may be of stamped metal, laminated boards, such as veneer, or a frame on which is stretched a fabric; it can be raised into the upper part of the frame when desired.

Within the upper part of the frame are disposed parallel metal sheets a, a'; b, b' and c, c'. The sash W' is adapted to enter between sheets b, b'; sash W^c between plates b', c and sash W^o between sheets c, c'. The curtain might enter between the sheets a, b and the screen between the sheets c', a'.

Disposed over the upper edge of each sash W', W^c and W^o is a tubular member 14 of any suitable material which is adapted to fill the space between the housing sheets and thus form an absolute weather stripping and soundproofing medium. Within this tube 14 is placed a resilient liner to hold it concentric, and to allow for the unequal coefficients of expansion of the metals to the glass.

The ends of the sheets a, b, c, etc. are secured at top within the frame, see Fig. 2. The sheet metal parts a, b, c, a', b' and c' may all be welded together at the top, so they form a unit construction, and slip as one piece up into the outer frame 50. It will be observed (see Fig. 14) that part 2 has a light running fit within the ways while the part 3 clears the ways. To the inner face of the guide 7 between the sash may be attached a bowed metal strip 7x (see Figs. 4 and 14), the edges of which may contact with the glass and act as weather stripping to exclude air and moisture from the interior of the guide.

A suitable weather stripping may be attached to the lower bar 4' of each sash. As shown (Figs. 2, 6, 13) at the bottom of the glass is a very thin sheet metal stripping 15, bent as shown. This strip is of spring material which has two lines of contact with the glass, as shown in Fig. 13. Welded to it is a curved strip 16, which may have fingers 16' on its outer edge, part 16 being of spring material but much heavier than part 15. This holds the spring 15 rigidly against the glass and the water can drip out over 16 and not freeze to cause rupture. These devices form a perfect weather seal.

At the bottom of the frame is a water plate 10,

see Figs. 1, 2 and 13. This water plate fits between the side plates 11, 11' (Fig. 1). The opening in the lower part of the sash may be finished by trimming of any suitable kind. As indicated in the drawings I have provided parts 37 and 38 made of thin material and of such shape that, like the frame, which is a standard cross section welded in a mitre joint at the corners, it finishes the inside and outside window trim. This window trim will be metal, and can take any of the beautiful finishes applied to automobile fenders, or other art metal work.

In Fig. 4 the window frame is shown as being temporarily clamped to the house frame by means of a strip 60 which holds the window frame in place until the outer finish 38 is placed.

In Fig. 2 the water seal plate 10 is shown in one piece and when all of the sashes are in the up position it can be removed and the seal and the whole lower ways assembly can be taken out as one piece. Then any sash can be lowered and very easily taken out.

The novel windows are delivered to the construction job with all the sash, screen and curtain retired into the upper compartment box, where they may be held apart by suitable packing such as corrugated board. And when the window is clamped into the house, each part can be lowered separately, the corrugated paper boards taken out; and the window is operative without any more adjustment on the part of the workmen.

The metal framing shown forms a rigid container for the novel sash and this novel sash shown in Figs. 10 to 12 has provision for different coefficients of expansion of the metal and the glass. The whole sash is supported by or hangs on part 2, which is the actuating member when it is vertically lifted, and the hinged member when it is used for a casement window (not shown).

In Figs. 6 and 7 I have illustrated how the aforesaid novel sash may be utilized in a window frame having upper and lower sashes. In this construction the frame 50 is constructed substantially as above described but upper hoods or chambers for the sashes are not used. In this construction I have shown two lower sashes which are like W' and W^o as above described and two upper sashes W² and W³ which alternate with the sashes W', W^o. The ways for each sash extend from top to bottom of the frame. Each of the sashes are provided with the lower weather seals 15, 16 as above described and the sashes W' and W^o are each provided on their upper edges under the rods 4 with a thin bowed strip 17 which when the upper sashes are fully raised and the lower sashes fully lowered, contacts with the metal strip 15 on the adjacent sash (see Fig. 6) and forms a close joint. Each of sashes W² and W³ is also provided on its upper edge and under the rod 4 with a grooved metal strip 4s which when the sash is raised enters grooves in or between filler strips 4t and 4w in the upper part of the frame and forms a strong joint.

The construction shown in Figs. 6 and 7 is adapted to a standard window in which the storm or outer window is mounted. This also uses the same principle of weather seal at the bottom of the window where it fits the ledges in the window sill. To form the seal between the upper and lower window glasses, the thin sheet spring material 17 is used which presses against the thin sheet metal strip 15 opposite, as shown. In each

case on the upper window, the part 16 is fastened to the thin sheet 15 by welding or brazing; and the stiff fingers 16' go up on the glass to hold the spring in position. This permits rain to drip off, and not collect so the water will freeze and rupture the structure.

The sash may be raised or lowered by any suitable mechanism but in Fig. 3 I have shown means for operating the respective sashes by means of 10 pinions engaging the rack bars 2. In this figure the actuating gear 21 is rigidly fastened to the shaft 28, and also carries a face friction clutch 23, rigidly fastened to the same shaft 28. 15 22 is a bearing permitting 28 either to rotate or have longitudinal motion within 22. At the outer end of 28 there is a squared or hexed socket to permit a crank to be inserted. If a crank is inserted and 28 pushed inwardly the gear teeth of 21 will slide longitudinally within the rack 20 on 2, and release the face friction clutch between 22 and 23; but as soon as the handle is removed from the socket in 28, the spring 24 will again engage the face friction clutch between 22 and 23, locking 21 and 22 to the frame. The 25 gear 20 is mounted on a tube 27. 27 likewise works within a bearing 19 which carries a friction clutch to work between 19 and 20. The outer end of the tube 27 is arranged for either an exterior or interior method of taking 30 rotational effort from a crank; and when the crank is engaged and the tube 27 is pushed in then 19 and 20 disengage and sash W' can be actuated either up or down.

The sash W' may be operated from the other 35 side by similar devices including the gear 33 engaging the rack 27 of the sash and fast to an inwardly movable rod 29 which is normally projected so as to hold gear 33 in engagement with the rack by a spring 31 interposed between the 40 fixed member 32 and the collar 30 on the rod 29, the inner end of the rod having a bearing and a lug 34 on the frame.

In the construction shown in Fig. 6 there are 45 four sashes and four operating gears are necessary. In this case (see Fig. 7) spur gear 20 is fastened rigidly to a tube, as shown, and the outer part 24 rigidly fastened to the same tube. 19x is fixed and becomes a bearing. This part 24 carries a socket hexed or squared to take rotation from an operating crank. When the operating crank is placed in 24 the latter pushed inward the spring is compressed and the face jaw clutches connecting 19x and 20 are released. The engagement between 19x and 20 is positive 55 and not frictional, as shown in Fig. 3, and I consider it the preferred construction. Shaft 25 squared at the end, is rigidly fastened to gear 21; and gear 21 is face jaw clutched to fixed member 22. In each construction the other two 60 sashes are operated by gears arranged in the same way on the opposite side and similarly numbered. The face jaw clutch is preferably made by forming a slot from the base of the tooth radial to the center, in which the face jaw clutches of the non-rotatable members engage. The aforesaid sash-operating devices form the subject matter of my companion application filed August 15, 1932, Serial No. 628,947.

The parts 10, 11 and 11' together with all of 70 the ways for the windows to operate in, are preferably welded together to form one integral structure. This window assembly will fit any type of house of present day construction, and has the outer storm window effect which adds

insulating qualities against heat and cold, and reduces outside noises.

The windows can be shipped from the factory ready for installation and operation. It can be clamped to the steel framing of the house; and when the outside and inside house finish is complete, then the final window trim can be put in place, all making for very rapid house assembly.

The low priced but highly efficient weather stripping methods prevent any transmission of outside atmosphere past the glass area. There is a multiple seal for the prevention of conducting either atmospheric or weather conditions from without to within. And the construction 85 renders it possible to add a cultural and artistic tone to window construction.

No claim is made herein for the weather stripping and the sash sealing devices, these being part of the subject-matter of a companion divisional application filed January 3, 1933, Serial No. 649,981. Also no claim is made herein for the window sash operating devices, these forming the subject-matter of a companion divisional application filed August 15, 1932, Serial No. 100 628,947.

I claim:—

1. In a window, a metal frame, sash guides within the frame, a sash mounted in said guides, and spaced sheets in the upper part of the frame 105 forming a pocket adapted to receive the sash when raised.

2. In a window frame as set forth in claim 1, a member on the upper edge of the sash adapted to contact with the walls of the pocket.

3. In a window, a metal frame, sash guides within the frame attached to the sides thereof, a sash mounted in said guides, spaced metal sheets in the upper part of the frame forming pockets adapted to receive the sash when raised, 115 and a member on the upper edge of the sash adapted to form a close joint between the upper edge of the sash and the adjacent sheets when the sash is raised.

4. A frame for metal windows comprising a 120 metal frame having exterior and interior flanges, and a metal water plate secured between the side members of the frame at the lower end thereof.

5. A frame for metal windows comprising a 125 metal frame having exterior and interior flanges, and a metal water plate secured between the side members of the frame at the lower end thereof, sash guides attached to the side members of the frame, and parallel sheets disposed 130 in the upper part of the frame between the guides forming a sash receiving pocket.

6. A frame for metal windows comprising a metal frame having exterior and interior flanges, a metal water plate secured between the side 135 members of the frame at the lower end thereof, and exterior and interior metal trims attached to the frame.

7. A frame for metal windows comprising a metal frame having exterior and interior flanges, 140 a metal water plate secured between the side members of the frame at the lower end thereof, and exterior and interior metal trims attached to the frame, sash guides attached to the side members of the frame, and parallel metal sheets 145 disposed in the upper part of the frame between the guides forming a sash receiving pocket.

8. A frame for metal windows comprising a metal frame having an exterior upturned flange and an interior down-turned flange, and a metal 150

water plate secured between the side members of the frame above the base thereof.

9. A frame for metal windows comprising a metal frame having an exterior upturned flange and an interior down-turned flange, and a metal water plate secured between the side members of the frame above the base thereof, sash guides attached to the inner side members of the frame, and parallel metal sheets disposed in the upper 10 part of the frame between the guides forming a sash receiving pocket.

10. A frame for metal windows comprising a metal frame having an exterior upturned flange and an interior down-turned flange, a metal water plate pivoted between the side members 15

of the frame above the base thereof, and exterior and interior metal trim attached to the sides of the frame.

11. A frame for metal windows comprising a metal frame having an exterior upturned flange and an interior down-turned flange, a metal water plate pivoted between the side members of the frame above the base thereof, and exterior and interior metal trim attached to the sides of the frame, sash guides attached to the side members of the frame, and parallel metal sheets disposed in the upper part of the frame between the guides forming sash receiving pockets.
